UNITED STATES PATENT OFFICE.

JOSEPH F. BROWN, OF WICHITA, KANSAS.

AIR OR WATER PRESSURE TANK.

1,347,934.

Specification of Letters Patent. Patented July 27, 1920.

Application filed October 1, 1919. Serial No. 327,309.

To all whom it may concern:

Be it known that I, JOSEPH F. BROWN, a citizen of the United States, residing at Wichita, in the county of Sedgwick and State of Kansas, have invented certain new and useful Improvements in Air or Water Pressure Tanks; and I do hereby declare the following to be a full, clear, and exact description of the invention, such as will enable others skilled in the art to which it appertains to make and use the same.

This invention relates to new and useful improvements in air or water pressure tanks used in connection with various kinds of systems and has for one of its objects the provision of a device of this character, which shall be simple, durable and efficient, and which may be manufactured and sold at a comparatively low cost.

Another object of this invention is the provision of means whereby the amount of metal employed to construct such devices is greatly reduced, thus reducing the expense of making the same, but still be capable of withstanding high pressure as well as being air and water-tight.

With these and other objects in view as will become more apparent as the description proceeds, the invention consists in certain novel features of construction, combination, and arrangement of parts, as will be hereinafter more fully described and claimed.

For a complete understanding of my invention, reference is to be had to the following description and accompanying drawings, in which:—

Figure 1 is a vertical sectional view of an air or water pressure tank constructed in accordance with my invention.

Fig. 2 is a vertical sectional view of the inner lining and hood therefor.

Fig. 3 is a front elevation of a reinforcing frame.

Fig. 4 is a plan view of an anchoring plate.

Referring in detail to the drawings, and especially to the method of constructing my invention, a hole 1 is dug or excavated in the ground to a depth equal to the height of the device and has its bottom wall of conical shape as illustrated at 2. A small amount of cement 3 is poured within the bottom of the hole 1 and allowed to set or become hard. The cement is approximately six inches in thickness and occupies the position at the apex of the conical portion 2 of the hole 1.

In forming my invention, the walls of the hole 1 are adapted to form the outer mold.

An inner shield 4 is constructed of metal or any other material suitable for the purpose and is of comparatively thin nature so as to reduce the expense of manufacturing the device. The lining 4 consists of a cylindrical body 5 having conical shaped upper and lower ends 6 and 7. The apices of the upper and lower ends of the lining 4 are provided with openings to permit a rod 8 to extend therethrough. The rod 8 extends through the lining or inner receptacle 4 at a point centrally thereof and carries at each end top and bottom plates 9 and 10. The plates 9 and 10 are preferably of circular formation having a plurality of circularly arranged openings 11 formed therein. The openings are adapted to receive the screw threaded ends of reinforcing rods 11 which are bent to conform to the contour of the lining 4 and arranged in spaced relation to the outer face thereof. The rods 11 receive upon their ends nuts 12 for retaining them in their proper position and also for securing them to the plates. These rods are further braced and held in relatively spaced relation by means of bands or hoops 13 that surround the body portion 5 of the lining 4 in spaced relation thereto and are connected to the rods in any well known manner. After the reinforcing rods 11 have been assembled or secured to their respective plates 9 and 10 and also to the hoops or bands 13 about the lining 4, said rods and lining are then positioned within the hole 1 permitting the bottom plate 10 to rest upon the cement 3. The rods which are disposed outermost of the lining are arranged and held manually or in any other well known manner in spaced relation to the wall of the hole 1. The space between the lining and the wall of the hole is then filled with cement up to the upper end of the cylindrical body portion 5 of the lining 4.

The upper conical shaped end of the lining 4 is provided with oppositely disposed openings to receive an inlet pipe 14 and an outlet pipe 15. The inlet pipe 14 terminates at a point at the upper end of the cylindrical portion 5 while the outlet pipe 15 extends downwardly within the lining and is received within a supporting strainer 16. The supporting strainer 16 is secured or formed onto the rod 8 at a point adjacent its lower end. The upper ends of the pipes

14 and 15 extend outwardly of the hole 1 and are adapted to be connected to various devices or to which the tank is used in connection with.

5 The rod 8 projects beyond the top plate 9 and carries at its upper end a conical shaped hood 17 which is disposed over the upper ends of the rods and the upper conical shaped end of the lining and arranged in 10 spaced relation thereto and has its lower edge disposed in a plane with the upper end of the cylindrical portion 5 of the lining and also in engagement with the wall of the hole 1. The hood 17 is substantially conical 15 shape having its apex flattened and provided with a pouring opening 18 in which the cement is adapted to be poured until the interior of the hood is entirely filled. The hood 17 is also provided with openings to 20 permit the inlet and outlet pipes 14 and 15 respectively to extend therethrough. After the cement has become set or hardened the hood may be removed if desired or can be left on the device if so desired. After the 25 cement has become thoroughly set or hardened, the upper portion of the hole 1 may then be filled with dirt so as to protect the upper end of the tank.

The tank may be constructed above ground 30 and also used above ground if desired by having a shell (not shown) supported in any suitable manner to form or act as a mold for the tank while the same is being constructed.

35 The following mixture has proven most successful in constructing my tank and consists of two-thirds sand, one-third cement, with one and one-half pounds of medusa which is a water-proof powder consisting of 40 fatty acids mixed with lime and the medusa is added to each one hundred pounds of cement used.

While I have shown and described the preferred embodiment of my invention, it 45 will be understood that minor changes in construction, combination and arrangement

of parts may be made without departing from the spirit and scope of the invention as claimed.

Having thus described my invention, what 50 I claim is:—

1. A tank comprising a lining constructed of comparatively thin material and having each end closed, an inlet pipe having communication with the interior of the lining, 55 a rod extending approximately along the major axis of the tank and through said lining, a strainer carried by said rod adjacent its lower end, an outlet pipe having one end disposed within said strainer and its 60 other end extending outwardly through the lining, a composition of material surrounding said lining, reinforcing means within the composition of material and having connection with the rod. 65

2. A tank comprising a comparatively thin lining having each end closed and disposed within a hole in the ground and arranged in spaced relation to the wall of said hole, inlet and outlet pipes having communication with the interior of the lining, 70 a rod extending approximately along the major axis of the tank and through said lining, plates carried by said rod and disposed exteriorly of the lining, a composition 75 of material surrounding said lining between the wall of the hole and the outer face of the lining, reinforcing rods embedded within said composition of material and relatively spaced and having their ends connect- 80 ed to the plates, bands holding the rods in relatively spaced relation and acting as a reinforcement for the composition of material, and a hood carried by the upper end of the rod and having a pouring opening. 85

In testimony whereof I affix my signature in presence of two witnesses.

JOSEPH F. BROWN.
